WINDOW LATCH

Application filed November 1, 1930, Serial No. 492,800, and in Great Britain November 17, 1927.

This invention relates to latching devices for sliding windows, particularly vehicle windows, and the principal object of the invention is to provide a latching device for a sliding closure comprising spring loaded frictional gripping means acting on the closure for holding same in any adjusted position and means for moving the gripping means against the spring action for the purpose of releasing the closure for adjustment when required.

A further object of the invention is to provide cam wedging means operated by the spring for pressing the frictional gripping device against the edge of the closure and means operable against the action of the spring to release the cam wedging device.

The invention will be more fully understood by reference to the accompanying drawing in which the only figure is an elevation partly in section of a latching device for slidable windows constructed according to the invention.

In the preferred embodiment of the present invention a slidable window of the compensated balanced type is guided at one side in a channel shaped metallic element 23, movable as hereinafter described in a second and fixed channel shaped member 24 extending vertically up the side of the window framework. To the outer side of the member 23 is fixed a wedge 25, or a number of wedges which taper towards its or their upper edge or edges, each wedge being mounted adjacent a freely rotatable roller 26 extending across the outer channel member 24. Each wedge has a pin 27 extending laterally therefrom which engages a slot 28 in one side of the channel member 24. An operating device for moving the inner channel member 23 and the wedge 25 into and out of locking position is mounted in a bracket 29 fixed relatively to the outer channel member 24.

In the form illustrated, this operating device comprises a bent lever 30, pivotally mounted at 31, and having a lower branch 32 pivoted to a link 33 having a resilient action by means of a spring 34 with a lever 35 pivotally mounted in an adjustable bearing 36, and connected by a link 37 to a bracket 38

fixed to the inner channel member 23. The lever 35 is normally urged to a position in which the cam 25 is operative to lock the window against movement by a spring 39 disposed around the rod 40 which passes through a slot in the lever 35.

With this arrangement, and with the parts in the position shown, the window is locked against movement, upward movement of the cam 25 to wedge against the roller 26 causing, owing to the inclined slot 28, a slight upward movement of the inner channel member 23, which thus effects a clamping action against the edge of the window, and prevents it from moving in either direction.

To release the window for adjustment, the end lever 30 is rocked in a clockwise direction about its pivot 31, this movement also rocking the lever 35, so that its left-hand end becomes depressed, moving the inner channel member 23 and the cam 25 downwardly. This frees the window edge from the frictional engagement by the inner channel member 23, and allows adjustment to any position, after which restoration of the lever 30 to the position shown will again lock the window in position.

In the accompanying drawing a fragment of the slidable window is shown at A, but the means for balancing the weight of the window is not illustrated as this may comprise any known spring or weight operated counter-balance and forms no part of the present invention. It will be readily understood that the window is guided at its edge remote from the channel member 23 by means of a suitably fixed guide channel forming part of the window frame (not shown).

We claim:—

1. A latching device for a sliding closure comprising a guide strip slidable longitudinally between the closure and its mounting, a spring urging said strip longitudinally in one direction, manual means for moving said strip longitudinally against the action of said spring, a cam carried by said guide strip and directed toward said mounting, a loose roller operatively disposed between said guide strip and mounting and engageable by said cam for pressing said guide strip into frictional

engagement with said closure when said guide strip is moved under the action of said spring and a pin and slot connection between said guide strip and said mounting for withdrawing said guide strip from frictional engagement with said closure when the guide strip is moved against the action of said spring.

2. A latching device for a sliding closure comprising a guide strip slideable longitudinally between the closure and its mounting, a cam on said guide strip having an inclined surface directed toward said mounting, a loose roller lying between said inclined surface and said mounting, an inclined slot and pin connection between said cam and said mounting, said pin and slot connection, roller and inclined surface being operative, when said guide strip is moved longitudinally in one direction to move said guide strip into frictional engagement with the closure and, when said guide strip is moved longitudinally in the opposite direction to release said guide strip from said closure, spring means urging said guide strip longitudinally in the first named direction, and manually operative means for moving said guide strip longitudinally in the last named direction.

In testimony whereof we have hereunto set our hands.

WILLIAM QUICK.
SYDNEY E. THOMAS.
FREDERICK WILLIAM BERWICK.
